FLOOR WAXER AND POLISHER

James G. Brooks, Los Angeles, Calif.

Application September 22, 1931
Serial No. 564,334

3 Claims. (Cl. 91—39)

This invention relates to improvements in combination floor waxers and polishers.

One of the objects of this invention is to provide a simple, efficient and inexpensive machine for waxing a floor as well as for polishing the same, after the waxing operation shall have been completed.

A further object of this invention is to provide novel means for feeding the wax in the machine 10 when a given surface thereof, in contact with the floor, has worn away.

Another object of this invention is to provide means whereby a rag or polishing cloth is designed to be used in conjunction with a perforated 15 bottom on the machine, the rag being employed to cover the wax surface directly exposed for contact with the floor, while a cover is provided for the rag and wax, about which the polishing cloth is designed to be secured.

20 Another important object of this invention is to provide a cover secured removably to the bottom of the machine whenever it is desired to change from a waxing operation to a polishing operation, inasmuch as it is not necessary to manipulate the machine to effect the change of 25 the cover fitting the bottom of the machine, and the polishing material being designed for removable attachment around the side wall as well as upon the bottom of this cover.

30 A further object of this invention is to provide means for quickly and instantly locking the casing of the machine, after wax shall have been applied thereto, for a waxing operation, in order to permit the wax feeding function to take place 35 properly.

In carrying out the details of the present invention it is proposed to employ a positive means 40 for advancing a follower-plate against the jelly-like wax introduced into the casing of the machine, the plate being independent from the feeding means, a hinged cover being also provided for closing the casing and for anchoring the wax feeding means.

A final object of this invention is to provide a 45 follower plate with a handle by means of which the follower plate is adapted to be removed from the casing, when the hinged lid has been opened. In conjunction with the feeding means a screw is provided for pressing the plate down when the 50 wax requires feeding.

In order to apply uniform pressure by means 55 of the set screw upon the follower plate in the casing of the machine it is designed to secure to the lower bearing end of the screw a series of radial arms, whereby an extended bearing surface is provided upon this set screw.

With the above and other objects in view my 60 invention consists in the arrangement, combination, and details of construction disclosed in the drawings and specifications, and then more par-

ticularly pointed out in the appended claims.

In the drawings, wherein similar reference characters designate similar parts thruout the respective views,

Figure 1 is a top plan view of my invention, 65 the handle being partly broken away,

Figure 2 is a top plan view of the feed screw,

Figure 3 is a side elevation of the machine,

Figure 4 is a top plan view, partly in section, 70 of the cover for the bottom of the casing of the floor waxer,

Figure 5 is an end elevation of the machine,

Figure 6 is a top plan view of the polishing cloth, or the like,

Figure 7 is a top plan view as well as end view 75 of the follower plate,

Figure 8 is a bottom plan view of the wlexer machine proper,

Figure 9 is a top plan view of the machine with 80 the cover broken away and in open position to disclose the follower plate,

Figure 10 is a top plan view of the machine showing the cover open and the follower plate removed,

Figure 11 is a longitudinal section taken thru 85 the casing of the machine, and

Figure 12 is a cross-sectional view of the machine.

The present invention consists of a casing broadly designated 10 having a preferably oblong 90 shape as shown in the figures of the drawings. The casing 10 has opposing longitudinal side walls of curvilinear shape designated 12, and end walls also formed curvilinear designated 14, these side walls being in the form of surfaces bulging out laterally. The preferred form of the invention, however, consists of the box-like casing 10 having base flanges, two of which extend longitudinally as at 12 and have convex edges, while the other two have end base flanges 14 and these are also formed with convex edges, the arrangement being such that the corners of the base flanges are formed narrowest. The interior of 95 the casing is designated 11.

The bottom surface of the casing 10 is formed 100 with an oblong countersunk chamber 15 and with a rectangular opening. Across this opening is secured a wire-mesh or reticulated member 16 which completely covers this opening and provides a porous surface thru the interstices of which the jelly-like wax A may be fed. It is proposed to employ a cloth spreader or sheathing 105 20, which has its sides 18 pressed against and secured upon the flanges 12, and 14 of the machine, being removably held in this position by 110 virtue of the cord or elastic band 17, by means 115 of which this sheathing is tied around the bottom of the machine.

The box or casing of the machine, 10, is designed to be closed by a flat lid or cover plate 120

21 which is reinforced by means of a central longitudinal rib 23 and the medial and end transverse ribs 22, in order to hingedly secure and mount this lid upon the casing it is necessary to provide a pair of integral upstanding webs 25 at one end of the casing 10, as shown in Figure 3, these webs projecting slightly above the casing to provide hinge lugs, designed to co-operate with the hinge lugs 24 formed upon one end of the lid 21, as shown in Figure 10. When the hinge lugs 24, abut the hinge lugs 25 pivot pins or a pivot pin or rod 26 is employed and is passed thru each pair or thru all of said lugs. In this manner the lid may be closed in flat contact with the upper edge of the casing, or else held in open position when it is desired to replenish the wax in the casing 10.

Inside of the casing 10 is a follower plate 43 which snugly fits this casing. The jelly-like wax will be placed first into the casing, so as to pass thru the interstices of the wire-mesh bottom and engage the necessarily porous cloth sheathing 20, to thereby be applied, as a coating, upon a floor when this casing is moved across the floor. In order to effect the adjustment of the follower plate 43 against the mass of wax when it becomes necessary to press down the wax, after the wax has been worn down, I provide a single set screw or feed screw 40, which at its bottom is provided with a cruciform spreader device consisting of the radial oppositely extending arms 42 and those arms integral to and at right angles to these arms, designated 43a. The screw 40 is threaded thru the center of the top lid 21 and above the lid is provided with a suitable operating handle 41.

As a means of manually operating the machine and to push and pull it across the floor to be waxed and polished, I provide a long handle 34, secured removably into a conical retainer 33 secured upon a U-shaped bail having the upper portion 32 and the parallel side arms 29, 30. The side arms 29, 30 of this bail are pivoted upon the sides of the casing 10; pivot pins 28 pass thru the lower ends or portions of the arms 29, 30 and are pivotally journaled in bearings 27 fixedly secured upon the base flanges 12 of the casing 10 of the machine. The bail is thus pivotally mounted centrally of the casing.

As a means for effecting the polishing of a floor by the same machine without the necessity of converting the casing, all it is necessary to do is to insert the bottom of the machine into a metal tray having the bottom 46 and the side walls 47, the latter having the same curvilinear outline as the machine itself. Around the side wall 47 of the tray is designed to be secured the polishing rag or material in the form of sheepskin or the like B, a flexible cord or elastic band 13 being employed to securely tie this material around the tray with the sides of the sheepskin or wooly material secured against the side of the tray and with the main body thereof extending across the under surface of the bottom 46 of this tray. The base flanges 12, 14 of the machine will snugly and frictionally fit into the side walls of the tray while the rag sheathing 20 thereof will overlie the floor 46 of the tray. The lid 43 is provided with a pivotal bail consisting of the handle 43' and the right angular side arms having the out-turned pintles 44 received movably in the lugs 45 carried medially upon the lid 43. When the bail is not in use it will overlie the lid as shown in Figure 7.

In operation, when the machine is used for

waxing floors the wax will first be placed in the casing 10. The follower plate 43 will then be pressed against the wax to cause the wax to spread out upon the cloth or rag sheathing 20. This is effected by giving a turn or turns to the handle 41 of the screw 40 and thereby turning the cruciform spreader attached to the bottom of the screw, which is then caused to advance downwardly, pressing the plate 43 against the wax. This action will be repeated as often as it is necessary to make the wax engage the cloth 20. As the operator pushes the machine across the floor, employing handle 34 for this purpose, a film of wax will be placed upon the floor uniformly and quickly. After the floor has thus been waxed and it is desired to polish it, the operator frictionally inserts the casing 10, and its rag sheathing 20 into the tray having the bottom 46 and side wall 47, and now the wax cannot come into direct contact with the floor, and the polishing material B may engage the floor and rub the wax in such a manner as to impart the desired waxy gloss upon the floor. By removing the retaining string, cord or elastic band 17 from the casing the rag may be removed. The lid 43 will be locked upon the casing, to assure a rigid mounting for the feed screw 40 as follows. A lug having a protruding lip 36 is formed medially upon one end of the casing 10; this lip has a recess upon its projecting end. There is a bail or rectangular link 38 whose lower shaft is pivotally mounted in a bearing fixedly secured at 39 upon the base flange 14 of the machine. This link 39 carries upon its upper shaft a roller 37, so when the link is in upright position, the roller 37 may ride wedgingly upon the lug 36 until it fits the recess of this lug, and this having been done the lid 43 will have been drawn into tight engagement with the upper edge of the casing 10.

I do not mean to confine myself to the exact details of construction herein disclosed.

What I desire to claim and secure by Letters Patent is:—

1. In combination a wax casing having a perforated wax discharging bottom, a follower plate in said casing, a rectangular wire bail hingedly mounted upon the upper face of the follower, a closure on the casing, an adjustable screw threaded into the closure so as to project below the closure, a series of radial flat arms carried rigidly by the lower end of the screw, being enclosed by the wire bail when the latter is in closed position overlapping the follower plate.

2. A wax box having a removable top, a perforated bottom and a continuous base flange skirting its bottom laterally, a web formed perpendicularly of the perimeter of the base flange so as to provide an inverted tray-like wax compartment in which wax leaving the perforated bottom may spread out, and a cheesecloth sheathing operatively closing the open interior of the compartment to confine the wax.

3. In a device as described, in combination, a wax holding case having provision at its bottom for discharging the wax, a follower plate adjustably positioned in said case to feed the wax downwardly, a top removably mounted upon the case, a screw tapped adjustably in said top and having a thumb head thereabove, and a cruciform spreader carried by the lower end of said screw and engaging the follower plate to adjust the latter.

JAMES G. BROOKS.
